UNITED STATES PATENT OFFICE.

GENE GARDNER BECKHARDT, OF BROOKLYN, NEW YORK.

STOCKING FRAME.

Application filed September 7, 1926. Serial No. 134,103.

This invention relates to stocking frames.

The principal object of the present invention is the production of a stocking frame characterized by improved features by virtue 5 of which the stocking frame will be more useful than those hitherto produced. In accordance with this object of the invention the stocking frame will be constructed to permit stockings of different kinds, especially 10 women's silk stockings to be conveniently dried after being washed; which may be dyed with the proper results; which may be displayed to show imperfections, if any; and which may be mended when necessary.

15 Another object of the invention is the provision of a stocking frame of the indicated character which is adjustable to accommodate stockings of different sizes, and one which will also maintain the stockings in the 20 proper shape when it is arranged on the frame after it has been washed. In accordance with this object of the invention the stocking frame is provided with means for releasably maintaining the foot and leg portions of the frame 25 in different adjusted positions together with a clamping means for clamping the top of the stocking to prevent the same from slipping down on the frame, and also provide means for suspending the frame with the stocking 30 thereon from some suitable support.

The nature of the invention and its distinguishing features and advantages will appear when the following specification is read in connection with the accompanying drawing, in which—

Figure 1 is a view of the stocking frame embodying the features of the present invention; the extensible or adjustable feature of the frame being illustrated in dotted lines.

Fig. 2 is a sectional view taken on the line 2—2 of Fig. 1, drawn on an enlarged scale, and illustrating the manner in which the top of the stocking is clamped to prevent the same from slipping down on the frame.

Fig. 3 is a detail view of a portion of one section of the frame.

Fig. 4 is a sectional view illustrating the manner in which the two sections of the frame may be adjusted with respect to each 5 other for displaying a stocking.

Referring now more particularly to Fig. 1 of the drawing, it will be apparent that in the illustrated embodiment, the stocking frame of the present invention will consist 5 of two sections, a section 10 and a section 11. The section 10 is bent and formed pref-

erably from a single piece of wire of suitable gage to provide a foot portion 12 and a leg portion 13. The member 14 of the leg portion 13 is bent substantially at a right 60 angle to provide an extension 15 having a loop 16 at the end thereof. The member 17 of the leg section is bent substantially at a right angle to provide an extension 18 which is looped at 19 and has a hook 20. The extension 18 is waved or crinkled as at 21. The extension 15 extends through the loop 19, whereas the extension 18 extends through the loop 16, and by virtue of the inherent flexibility of the extensions 15 and 18 coaction 65 will be set up between the loop 16 and the corrugations of the crinkled portion 21 to releasably maintain the members 14 and 17 of the leg section 13 in any desired relationship with respect to each other to conform 70 to the shapes and sizes of different stockings. The section 11 of the stocking frame, in the present instance is bent and formed from a single piece of wire of suitable gage to provide a member 22 and members 23 respectively at opposite ends of the member 22. Each of the members 23 has a loop 24. The extension 15 extends through the loop 24 of one of the members 23, whereas, the extension 18 extends through the loop 24 of the other member 23. The section 11 is thus pivotally or hingedly connected to the section 10 and is therefore adapted to be moved with respect thereto. The hook 20 and the member 22 with a portion of which the hook 20 90 coacts, constitutes a clamping means for clamping the top of a stocking to hold the stocking from sliding down on the frame, as shown most clearly in Fig. 2. The hook 20 also serves for suspending the frame in its 95 entirety from a suitable support such as a clothesline. It is to be noted that when the leg portion 13 is extended, as shown in Fig. 1 that the hook 20 and member 22 nevertheless serve as a clamping means for the purpose mentioned. The section 11 also serves as a means which may be grapsed in one hand to conveniently hold the frame for displaying a stocking arranged thereon when inspecting the stocking for imperfections, 100 and makes easy the arrangement of a stocking on the frame when held in one hand, while the stocking is slid on the frame with the other hand. Furthermore when the section 11 is disposed at an angle with respect 110 to the section 10, as shown in Fig. 4, the section 10 may be disposed in an inclined dis-

play position. This is an expedient which allows stockings to be displayed in shop windows, and a price and display card may be secured to the hook 20. The section 11 5 also serves to hold the sides of the stocking separated so that the same may be easily mended.

It is to be understood that the invention is not restricted to the precise arrangement of 10 parts shown and described, as details of construction may be modified and rearranged without departing from the spirit of the invention, the scope of which is limited only by the terms of the appended claims.

15 I claim:

1. A stocking frame comprising an upper section, a lower section with which the upper section is connected, the lower section being bent and formed from a single piece of wire 20 to provide foot and leg portions, and means for releasably retaining said portions in different adjusted positions with respect to

each other; the upper section being movable relatively to the lower section to a position to serve as a prop to hold the lower section in 25 an inclined displaying position.

2. A stocking frame including a lower foot and leg section, an upper section connected with the foot and leg section serving as a handle for holding the frame while putting a stocking on the foot and leg section, said upper section being movable relatively to the foot and leg section to a position with respect thereto to serve as a prop to hold the foot and leg section in an inclined displaying position, said upper section having a cross member, and a hook connected with the upper end of the lower foot and leg section, said hook adapted to coact with the cross member to clamp the upper edge of a stocking to securely hold the stocking in stretched condition on the frame, and said hook also serving for hanging up the frame.

GENE GARDNER BECKHARDT.
